(57) **CLAIM**

The ornamental design for a translucent mat with ribbed pattern, as shown and described.

DESCRIPTION

FIG. 1 is a side view of the translucent mat with ribbed pattern, the right side view of the figure is representative of the top plan view in FIG. 2;

FIG. 2 is a top plan view;

FIG. 3 is an enlarged detail view of area 3 circumscribed within or on FIG. 1; and,

FIG. 4 is an enlarged detail view of area 4 circumscribed within or on FIG. 2.

The portions of the translucent mat with ribbed pattern shown in broken lines form no part of the claimed design.

1 Claim, 1 Drawing Sheet
